FIG. 2

FIG. 1

INVENTOR,
Leonardo Guardino
BY
H. Lee Holmes
ATTORNEY.

UNITED STATES PATENT OFFICE

102,947

DESIGN FOR A SIGNAL LAMP FACEPLATE

Leonardo Guardino, Brooklyn, N. Y.

Application October 28, 1936, Serial No. 65,554

Term of patent 14 years

To all whom it may concern:

Be it known that I, Leonardo Guardino, a citizen of the United States, residing in Brooklyn, county of Kings, State of New York, have invented a new, original, and ornamental Design for a Signal Lamp Faceplate, of which the following is a specification, reference being had to the accompanying drawing, forming part thereof:—

Figure 1 is a view in front elevation of a signal lamp faceplate showing my new design.

Figure 2 is a view in side elevation thereof.

I claim:

The ornamental design for a signal lamp faceplate as shown.

LEONARDO GUARDINO.
